SHIPPING CASE AND SUPPORTING FRAME
FOR REFRIGERATING APPARATUSEdward Heitman and Arthur H. Sack, Detroit,
Mich., assignors to Kelvinator Corporation,
Detroit, Mich., a corporation of Michigan

Application April 8, 1931. Serial No. 528,502

3 Claims. (Cl. 217—36)

This invention relates to refrigerating apparatus and more particularly to a shipping case for such apparatus which may also be used as a supporting frame therefor.

At the present time there are two general types of domestic mechanical refrigerators. The older and more common type is that in which the condensing unit is positioned in a compartment at the bottom of the cabinet. This type of structure is sometimes varied by locating the condensing unit exteriorly of the cabinet, although installations of this kind are fast becoming obsolete. The other general type of mechanical refrigerator is one in which the condensing unit is placed on top of the cabinet or in the upper part thereof. In the latter type the condensing unit is customarily rigidly connected to the cooling unit and the two are removable from the cabinet without breaking the connections therebetween. Accordingly the cooling unit and condensing unit are adapted to be operatively connected together at the factory and transported wherever desired for installation. This has greatly facilitated the handling of such units for replacement and repair.

Heretofore it has not been practical to transport the refrigerating apparatus employed in the other type of mechanical refrigerator in which the condensing unit is disposed in a compartment at the bottom of a cabinet, as a unit, because of the likelihood of damage to the flexible conduits connecting the condensing unit to the cooling unit and because of the difficulty of handling these two parts as a unit while joined together only by flexible tubing.

This invention accordingly has as its principal object the provision of a structure adapted for use as a shipping case and supporting frame for refrigerating apparatus of this type whereby such apparatus may be satisfactorily handled and transported without breaking the connections between the condensing unit and the cooling unit. By the use of this invention it is possible to retain the advantages of the mechanical refrigerator having a condensing unit at the bottom portion thereof while at the same time the advantages resulting from locating the condensing unit at the top of the cabinet are made available.

In the drawings:

Figure 1 is a side elevation of the shipping case embodying this invention in its closed position with parts broken away showing the location of the refrigerating apparatus within the case;

Figure 2 is a side view in elevation showing the shipping case opened up as a supporting frame

for the refrigerating apparatus secured thereto;

Figure 3 is an end view in elevation showing the refrigerating apparatus on the supporting frame in position to be inserted into a refrigerator cabinet;

Figure 4 is a front view of a refrigerator cabinet showing the refrigerating apparatus in position within the cabinet.

The shipping case 10 embodying this invention is preferably formed of wood and comprises a substantially rectangular box having solid side walls and spaced slats forming its other walls. The bottom wall of the case consists of a plurality of spaced slats 11 held together by cross members 12. The cross members are secured to the slats 11 by means of nails 13. One end wall 14 is rigidly secured to the slats 11 forming the bottom wall. The wall 14 comprises a pair of spaced upright slats 15 joined together by means of three cross members 16. The members 16 are nailed to the slats 15 by nails 17. The end wall 14 is further strengthened by a cross member 20 positioned on the opposite side of the vertical members 15 from the cross members 16 and secured to both of these members by means of bolts 21. A groove 22 is provided at one end of the member 20 for a purpose to be described presently. The lower cross member 16 extends beyond the lower extremity of the upright members 15 which rest upon the bottom wall members 11 and is fastened to the members 11 as well as the upright members. The joint between the end wall 14 and the bottom wall is made rigid by means of a bracket 18 comprising a strip of sheet metal having flanged edges one of which is secured to the vertical end wall by means of bolts 19, the other being secured to one of the cross members 12 of the bottom wall by similar bolts.

The top wall consists of two spaced lateral members 23 rigidly held in position by cross members 24 secured thereto by nails 25. The members 23 are also rigidly secured to an end wall 26. A third lateral member 27 disposed between the members 23 and spaced therefrom forms a portion of the top wall and is removably secured in position by means of screws projecting therethrough and into the end wall 26 and the cross members 24. The top wall is rotatably secured to the end wall 14 by means of hinges 32 which are fastened to the respective walls by bolts 33.

The end wall 26 consists of a pair of cross members 28 secured to three spaced vertical members 29 by means of nails 30. A third vertical

100

105

110

member 31 is positioned between the cross members 28 and secured to these members and the middle vertical member 29. The end wall 26 is rigidly secured to the top wall by means of a sheet metal plate 18 identical with the plate used for securing the end wall 14 to the bottom wall. The end wall 26 is preferably detachably secured to the bottom wall by means of removable screws 33a projecting through the end wall 10 and into the members 11 of the bottom wall. The screws 33a may be dispensed with if desired as other means indirectly secure the end wall to the bottom wall.

The side walls consist of a thin panel 34 secured to the inner side of a frame comprising a pair of horizontal members 35 secured to a pair of vertical members 36. The side walls are removably secured in position by means of bolts 37 projecting through the frame members and into openings 38 provided for that purpose in the members 29, 23, 15 and 11. The side walls when in position are adapted to secure the shipping case 10 in a closed position without the use of the screws 33a, heretofore described as being adapted to detachably secure the end wall 26 to the bottom wall.

When the side walls are removed and the screws 33a withdrawn, in the event that they are used, the end wall 26 and the top wall may be rotated counterclockwise from the position shown in Figure 1 to the position shown in Figures 2 and 3. It may be secured in this latter position by removing the removable lateral member 27, forming a part of the top wall and positioned between the members 23, and dropping it down through the opening between the cross members 16 and 20 forming a part of the end wall 14. In this position the member 27 prevents the top wall from being rotated to its closed position. When it is desired to close the case again, the lateral member 27 is withdrawn from the position shown in Figure 3. The top wall and the end wall 26 may then be rotated in clockwise manner to the position shown in Figure 1 and the removable side walls secured in place by means of the bolts 37.

The case 10 when opened as illustrated in Figures 2 and 3 is designed to support a refrigerating apparatus for a mechanical refrigerator in relatively the same position that that apparatus will occupy in the refrigerator. The size of the shipping case will accordingly vary with the size of the refrigerator cabinet and the refrigerating apparatus. In Figure 3 the shipping case 10 is shown positioned in front of a cabinet 39. The refrigerating apparatus supported by the frame 10, which will be described more in detail presently, is adapted to be placed within the cabinet 39 as illustrated in Figure 4.

The refrigerating apparatus supported by the frame 10 and adapted to be positioned within the refrigerator cabinet 39, consists of a condensing unit 40 and a cooling unit 41 operatively connected together by refrigerant conduits 42 and 43. The condensing unit 40 is built upon a base 44, and consists of a compressor 45, a motor 46 operatively connected to the compressor by means of a belt 47, a refrigerant condenser 48, and a liquid receiver 49. Cooling air is passed through the condenser 48 by means of a fan 46a carried by the shaft of the motor 46. The condensing unit 40 is securely fastened to the bottom of the shipping case 10 by means of bolts 54 projecting through openings in the base 44, the cross

members 12, and the lateral members 11. Nuts 55 lock the bolts 54 in position.

The cooling unit 41 comprises a header or vaporizer 50 having a plurality of parallel depending pipe loops 51 connected thereto. The pipe loops enclose a sheet metal freezing tray sleeve 52 divided into two compartments by a horizontal partition 53. A bracket 44 is provided on the exterior surface of the freezing tray sleeve 52 for the reception of a thermostat element. Liquid refrigerant is delivered to the vaporizer 50 from the liquid receiver 49 by means of the conduit 42. The suction line 43 joins the outlet opening in the vaporizer 50 to the low side of the compressor 45. The conduits 42 and 43 are fitted into the slot 22 provided at one end of the cross member 20. The cooling unit 41 is secured to the frame 10 by means of hanger straps 56 carried by the vaporizer 50 which are adapted to receive the free extremities of bolts 54 projecting through the members 29. Nuts 55 secure the hanger straps in position on the bolts and against the members 29.

The shipping case and supporting frame 10 is used in the following manner. The refrigerating apparatus including the condensing unit 40, the cooling unit 41 and the refrigerant conduits 42 and 43 is secured to the frame 10 in the manner already described while the frame is in the position illustrated in Figure 2. Removable panel 27 is then withdrawn from the position shown in Figure 3, and the top wall and end wall 26 of the frame rotated in clockwise manner to the position illustrated in Figure 1. The panel 27 is then secured in position as part of the top wall. The conduits 42 and 43 are prevented from being damaged when the case is closed as illustrated in Figure 1 by reason of their being secured in the notch 23. After the top wall and end wall 26 are rotated to the position shown in Figure 1, the side walls are secured in place by means of the bolts 37. The screws 33a may then be inserted if desired as additional securing means for the end wall. The refrigerating apparatus in the shipping case 10 may then be transported to any desired destination and immediately made available for insertion into the refrigerator cabinet 39 by opening the shipping case to the position shown in Figure 3. The removable panel 27 is of course removed from the top wall and lowered into the groove between the cross members 20 and 16 to lock the frame in its open position.

Before the refrigerating apparatus is moved into the cabinet 39 it is made completely ready to operate by the opening of suitable valves and by the addition of a fuse box 57 to the motor 46. The fuse box has two electric cables 58 and 59 connected thereto. The cable 58 is provided with an electric plug at its free extremity which is adapted to be inserted into the conventional wall socket. The free extremity of the cable 59 terminates in a thermostat switch 60. The temperature responsive element 61 of the thermostat 60 is adapted to be clampingly received by the clamps 54 carried on the exterior surface of the freezing tray sleeve 52. When the refrigerating apparatus is properly prepared for insertion into the cabinet 39, the bolts 54 securing the condensing unit to the bottom wall of the case 10 are removed and the condensing unit is placed in the machinery compartment 62 of the refrigerator cabinet. Suitable securing means, not shown, are provided for securing the condensing unit in position within the cabinet. After the condensing unit has been installed, the

bolts 54 securing the cooling unit 41 to the end wall 26 of the frame are removed and the cooling unit is positioned within the refrigerating compartment 63 of the cabinet 39. The cooling unit 41 is secured in position within the compartment 63 by the hanger straps used to secure it to the frame 10. Bolts depending from the top wall of the refrigerating compartment 63 are adapted to project through openings in the hanger straps 56. The straps are secured in position on the bolts by the nuts 55 used in securing the cooling unit to the frame 10. Refrigerant conduits 42 and 43 and the electrical cable 59 are placed in a groove in the door frame of the cabinet 39 which is closed by a removable molding. The mechanical refrigerator is then ready for use. The refrigerating apparatus may be readily removed from the cabinet 39 by reversing the procedure just described.

From the foregoing description it will be apparent that this invention provides means whereby refrigerating apparatus of the type wherein the condensing unit is disposed in the lower portion of a refrigerator cabinet and the cooling unit in the upper portion thereof may be readily removed as a single unit and transported in that condition without injury to the refrigerating apparatus. Refrigerating apparatus of this type is thereby made more accessible for repairs and replacement.

What is claimed is,

1. A shipping case for refrigerating apparatus comprising a substantially rectangular box having removable side walls, a bottom wall adapted to support a refrigerant condensing unit and rig-

idly secured to an end wall, a top wall rigidly secured to the opposite end wall, said last mentioned end wall being adapted to support a refrigerant cooling unit and being detachably secured to the bottom wall, and means for rotatably securing the top wall to the first mentioned end wall whereby the end wall supporting the refrigerant cooling unit may be swung upwardly to a horizontal position.

2. A shipping case for refrigerating apparatus comprising a substantially rectangular box having removable side walls, a bottom wall adapted to support a refrigerant condensing unit and secured to an end wall, a top wall rigidly secured to the opposite end wall, said last mentioned end wall being adapted to support a refrigerant cooling unit and being detachably secured to the bottom wall, means for rotatably securing the top wall to the first mentioned end wall whereby the end wall supporting the refrigerant cooling unit may be swung upwardly to a horizontal position, and means for securing the said end wall in the horizontal position.

3. A shipping case comprising a substantially rectangular box having removable side walls, an end wall detachably secured to a bottom wall, a top wall hinged to the opposite end wall whereby the top wall may be moved to a vertical position, and a removable slat in the top wall adapted to slide into a groove in the end wall whereby the top wall may be secured in a vertical position.

EDWARD HEITMAN.
